UNITED STATES PATENT OFFICE.

CLARA E. MAPES, OF NEW YORK, N. Y.

RUBBER SHOE.

No. 892,171.

Specification of Letters Patent.

Patented June 30, 1908.

Application filed April 14, 1906. Serial No. 311,719.

To all whom it may concern:

Be it known that I, CLARA E. MAPES, a citizen of the United States, residing at New York, in the county of New York and State 5 of New York, have invented a new and useful Rubber Shoe, of which the following is a specification.

This invention relates to that class of rubber overshoes known as sandals, comprising 10 a sole portion having vertical sides and toe covering and with an integral strap extending around the heel, and with or without an additional strap across the instep, and has for its object to provide a simply constructed attachment whereby the sandal may be supported upon the foot.

With these and other objects in view which will appear as the nature of the invention is better understood, the invention 20 consists in certain novel features of construction as hereafter fully described and claimed.

In the accompanying drawings forming a part of this specification and in which corresponding parts are denoted by like designating characters, is illustrated the preferred 25 form of the embodiment of the invention capable of carrying the same into practical operation.

In the drawings:—The figure represents a 30 perspective view of the improved overshoe.

The improved article comprises a sole portion 10 having vertical sides 11—12, a toe portion 13, a heel strap 14, and preferably with an instep strap 15, these parts being of 35 the usual construction, of rubber. The heel strap 14 is generally arranged to bear over the heel portion of the shoe at its juncture with the ankle, and sufficiently elastic to hold the sole portion with its sides and toe 40 portion in position, but in order to do this, it is necessary that the heel strap shall draw the sole portion with considerable force and this strain causes the overshoe to produce an unpleasant drawing effect upon the foot of 45 the wearer, and if the heel strap is arranged sufficiently loose to prevent this drawing effect, it is liable to work loose and drop down over the heel.

The constant motion of the foot in walking 50 causes the heel strap to work loose unless it be sufficiently strained to resist this loosening effect, and as before stated, if thus left loose, it is liable to fall over the heel and release the overshoe. The principal object of 55 the present invention is to provide a simply constructed attachment whereby the heel

strap is held in position, and prevented from displacement even when left comparatively loose, so that the sole portion with its sides and toe covering may be worn with sufficient 60 looseness to prevent the drawing effect upon the foot, while at the same time held in position upon the foot and prevented from displacement therefrom by the movement of 65 the foot.

The improvement consists in forming two straps 16—17 extending from the heel strap intermediate its sides, and preferably integral therewith, and providing a suitable fastening means to connect the free ends of the 70 straps over the lower portion of the ankle or the upper portion of the instep of the wearer, this fastening means being preferably some form of an easily operated buckle, as represented at 18. By this simple means, an 75 overshoe of comparative looseness and corresponding comfort may be worn without danger of attachment or displacement by the foot motion. Another object gained by this construction is that the same pair of overshoes 80 may be worn with different forms of shoes, as the strap 17—18 may be readily adjusted by means of the buckle to adapt the overshoe to different sizes or forms of shoes.

The device is very simple in construction, 85 can be inexpensively manufactured, and does not add materially to the cost of the article to which it is applied.

Having thus described the invention, what 90 is claimed as new is:—

A heelless overshoe comprising a sole portion having side and toe portions, a heel strap integral with the side portions and extending upwardly and rearwardly therefrom for engagement with the heel portion of 95 a shoe, an instep strap integral with the side portions of the overshoe and extending continuously from one side to the other thereof, supporting straps extending forwardly and upwardly from opposite portions of the heel 100 strap and integral with said heel strap, and means for adjustably connecting the supporting straps, said supporting straps and heel strap constituting an ankle band for encircling a shoe above the heel and instep. 105

In testimony that I claim the foregoing as my own, I have hereto affixed my signature in the presence of two witnesses.

CLARA E. MAPES.
